DESIGN FOR A SUPPORT FOR CLOTHING OR THE LIKE

Marguerite Stringfellow and Nancy R. Lynn,
Tampa, Fla.

Application February 4, 1948, Serial No. 144,254

Term of patent 14 years

(Cl. D33—3)

To all whom it may concern:

Be it known that we, Marguerite Stringfellow and Nancy R. Lynn, citizens of the United States, residing at Tampa, in the county of Hillsborough and State of Florida, have invented a new, original, and ornamental Design for a Support for Clothing or the like, of which the following is a specification, reference being had therein to the accompanying drawing, forming part thereof, in which

Figure 1 is a perspective view of a support for clothing, or the like, showing our new design.

We claim:

The ornamental design for a support for clothing, or the like, as shown.

MARGUERITE STRINGFELLOW.
NANCY R. LYNN.
